No. 759,722.

PATENTED MAY 10, 1904.

M. C. KRUEGER.

ELECTRIC HEATER OR RHEOSTAT.

APPLICATION FILED OCT. 6, 1902.

NO MODEL.

UNITED STATES PATENT OFFICE.

MAX C. KRUEGER, OF CHICAGO, ILLINOIS, ASSIGNOR, BY MESNE ASSIGNMENTS, TO THE MAGNETO ELECTRIC COMPANY, OF AMSTERDAM, NEW YORK, A CORPORATION OF DELAWARE.

ELECTRIC HEATER OR RHEOSTAT.

SPECIFICATION forming part of Letters Patent No. 759,722, dated May 10, 1904.

Application filed October 6, 1902. Serial No. 126,039. (No model.)

To all whom it may concern:

Be it known that I, MAX C. KRUEGER, a citizen of the United States, residing at Chicago, in the county of Cook and State of Illinois, have invented a new and useful Improvement 5 in Electric Heaters or Rheostats, of which the following is a specification.

This invention relates to electric heaters and rheostats.

10 The object of the invention is to provide a construction of electric heater and rheostat which is simple, economical, and efficient.

The invention consists substantially in the construction, combination, location, and arrangement of parts, all as will be more fully hereinafter set forth, as shown in the accompanying drawings and finally pointed out in the appended claims.

Referring to the accompanying drawings, 20 and to the various views and reference-signs appearing thereon, Figure 1 is a view in central longitudinal section on the line 1 1 of Fig. 2 and showing a construction of electric heater and rheostat embodying the principles 25 of my invention. Fig. 2 is a transverse section on the line 2 2 of Fig. 1 looking in the direction of the arrows. Fig. 3 is a detached detail view in perspective, showing a resistance-plate and the arrangement of conducting 30 and insulating strips at the ends thereof. Fig. 4 is a view in side elevation and showing means for insuring separation of the resistance-plates. Fig. 5 is a transverse section on the line 5 5 of Fig. 4.

35 The same part is designated by the same reference-sign wherever it occurs throughout the several views.

In carrying out my invention I suitably mount upon an insulating-plate or base-resistance strips or plates superposed the one upon the other and suitably clamped together, with conducting-strips and insulating-strips alternately arranged between adjacent ends of said strips to form a continuous circuit through 45 all the resistance-plates, together with suitable binding projections, so that any desired number of the plates may be cut out of cir-

cuit. This, in brief, is a general statement of the manner of carrying my invention into practical operation.

50 In the drawings, reference-sign A designates the insulating-base, and B the resistance-plates. These plates are in the form of strips and may be of any suitable or desired length and of any suitable material. I have found 55 tin to be efficient for this purpose and to well answer the purpose, and being cheap and easily manipulated its use greatly reduces the cost of construction of the heater or rheostat. The desired number of resistance plates or strips 60 to be incorporated in a heater or rheostat being produced, said strips or plates are assembled by superposing the same the one upon the other. In superposing these strips or plates upon each other an insulating plate or 65 strip C and a conducting strip or plate D are placed between each end of each strip and the next adjacent resistance strip or plate above and below the same, respectively. For instance, an insulating plate or strip C is located between one end of a resistance strip or plate and the adjacent end of the next resistance strip or plate lying beneath it, while at the opposite ends of said resistance strips or plates a conducting-plate D is interposed. 70 The reverse of this arrangement is observed 75 on the upper side of said resistance plate or strip, as clearly shown in Fig. 3, thus building up the heater or rheostat by a succession of resistance plates or strips, each strip or plate being insulated at one end from the next adjacent strip or plate on one side thereof and conductively connected at its opposite end to the next adjacent resistance strip or plate lying on the opposite side thereof. 80 The lowermost resistance strip or plate of the series is arranged to rest upon a block or other support E upon the base-plate A, and similarly a clamping-block F is arranged to bear against the upper side or face of the 85 uppermost resistance strip or plate. All the parts may be securely and rigidly clamped together in any convenient manner—as, for instance, by means of suitably-insulated rods

G, passing through the parts and the base-plate, and set-nuts H, turned up upon the threaded ends of said rods.

From the foregoing description it will be seen that I provide an exceedingly simple and inexpensive construction of electric heater and rheostat in which the parts may be readily and quickly assembled in proper relation.

If desired, and as shown, the clamping-rod 5 G may pass through holes formed in the ends of the resistance strips or plates and of the insulating and conducting separating strips or plates, as most clearly shown in Fig. 3.

If desired, and in order to secure strength 10 and rigidity, and preferably, the resistance strips or plates are channeled or bent into substantially V or other desirable shape in cross-section, as clearly shown in the drawings. In this event the supporting-blocks E 15 and the clamping-blocks F, as well as the separating, insulating, and conducting strips or plates C D, are similarly shaped. This V-shaped or grooved construction of resistance-plate affords strength and rigidity to 20 the entire construction and serves to prevent the same from buckling or bending during expansion and contraction thereof, which in devices of this nature has been a source of considerable trouble and difficulty.

If desired, and in order to insure separation of the resistance-plates throughout their 25 entire length, an insulating-strip J may be interposed between the resistance strips or plates B at one or as many points as may be necessary, this strip being passed back and forth in alternate directions between adjacent 30 resistance strips or plates, as will be clearly understood from the drawings.

If desired, conducting projections K may 35 be interposed at proper intervals for the purpose of affording means for connection of leading-wires and through which any desired number of resistance strips or plates may be included in operating-circuit.

An electric heater or rheostat embodying 40 the principles of my invention is assembled and built up as follows: A plate or strip D is placed with its ends resting upon supporting-blocks E. An insulating and separating plate 45 C is then placed upon said resistance plate or strip at one end, and a conducting strip or plate D is placed upon the other end. Then the next resistance strip or plate is placed in position with its ends resting on said insulating and conducting strips or plates C D. A 50 conducting strip or plate D is then placed over the end of said second strip or plate which rests upon the insulating strip or plate, and an insulating strip or plate is placed over 55 that end of said resistance plate or strip which rests upon the conducting and separating strip or plate, and so on until the desired 60 number of resistance strips or plates are assembled. The parts are then firmly and securely clamped together and the leading-

wires attached, as described, and the device is ready for use. If additional separation of the resistance strips or plates is necessary, an insulating-strip J is interposed, as described, at one or any desired number of points between 70 the ends of said strips, said insulating-strip being passed back and forth between adjacent resistance-strips.

It will be seen that in a rheostat or heater constructed as described ample space is provided between adjacent resistance-strips for 75 ventilation.

I desire it to be understood that my invention is not to be limited or restricted to the exact details of construction and arrangement 80 shown and described, as many changes and variations in the details thereof would readily suggest themselves to persons skilled in the art and still fall within the spirit and scope of 85 my invention.

Having now set forth the object and nature 90 of my invention and a construction embodying the principles thereof, what I claim as new and useful and of my own invention, and desire to secure by Letters Patent, is—

1. An electric heater or rheostat comprising a series of longitudinally-bent sheet-metal resistance-plates superposed upon each other, separating-plates interposed between adjacent 95 ends of said strips, said separating-plates being alternately of resistance and conducting material and bent to correspond with said resistance-plates, and means for clamping said parts together, as and for the purpose set forth.

2. An electric heater or rheostat comprising 100 a series of channeled or grooved resistance strips or plates superposed upon each other and alternately insulated and electrically connected together at the respective ends thereof, and means for clamping said parts together, 105 as and for the purpose set forth.

3. An electric heater or rheostat, comprising 110 a series of resistance-plates V-shaped in cross-section and superposed in nested relation upon each other, and insulating and conducting strips or plates interposed between adjacent ends of said resistance strips or plates and arranged to form a continuous circuit back and forth from one strip to another, and means for clamping all of said parts together, as and for 115 the purpose set forth.

4. An electric heater or rheostat comprising a series of longitudinally-bent sheet-metal resistance-plates superposed upon each other, separating-plates interposed between adjacent 120 ends of said strips, said separating-plates being alternately of insulating and conducting material and bent to correspond with said resistance-plates, and conducting projections for attachment of leading-wires, all combined and arranged, as and for the purpose set forth.

5. In an electric heater or rheostat, an insulating base-plate, supporting-blocks mounted thereon, longitudinally-bent resistance strips or plates superposed upon each other 130

and supported upon said blocks, separating-plates for the ends of said resistance strips or plates, said separating-plates being alternately of insulating and conducting material and 5 bent to correspond with said resistance-plates, clamping-blocks superposed upon the ends of the uppermost resistance-plate, and clamping-screws for clamping all of said parts together, all combined and arranged, as and for the purpose set forth.

6. In an electric heater or rheostat, the combination with an insulating base-plate, supporting-blocks mounted thereon, resistance strips or plates superposed upon each other 15 and resting at their ends upon said blocks, separating-plates interposed between adjacent

ends of said resistance strips or plates, said separating-plates being respectively of insulating and conducting material, clamping-blocks superposed upon the ends of the uppermost of said resistance strips or plates, securing-bolts passing through all of said parts, and set-nuts mounted thereon for clamping said parts together, all combined and arranged, as and for the purpose set forth. 20 25

In witness whereof I have hereunto set my hand, this 30th day of September, 1902, in the presence of the subscribing witnesses.

MAX C. KRUEGER.
